HAND TOOLING DEVICE FOR USING SIZED
GOLD AND OTHER DECORATIVE LEAF

Albert Sternberg, Fort Lee, N. J.

Application July 28, 1938; Serial No. 221,674

8 Claims. (Cl. 41—7)

This invention relates to new and useful improvements in a hand tooling device for using sized gold and other metallic leaf and color transfer leaf.

- 5 The invention contemplates the construction of a tooling device as mentioned which is adapted to carry out a hot stamping process using metallic leaf such as gold, silver, palladium in sized form, and various transfer colored leaf. 10 Various leathers, imitation leather, fancy paper, book cloth, silk, wood, parchment and other materials may be decoratively imprinted with a tooling device according to this invention.

The invention contemplates the construction 15 of a hand tooling device which is characterized by a support member having a handle element on the top thereof by which it may be conveniently manipulated. It is contemplated that a stamping die wheel be rotatively mounted on the bottom of the support member; that a means be provided for heating the stamping wheel; that a supply container for a ribbon of leaf be mounted thereon and constructed and operated in a novel manner.

20 For further comprehension of the invention, and of the objects and advantages thereof, reference will be had to the following description and accompanying drawings, and to the appended claims in which the various novel features of the invention are more particularly set forth.

25 In the accompanying drawings forming a material part of this disclosure:

Fig. 1 is a perspective view of a hand tooling device constructed according to this invention.

30 Fig. 2 is a perspective view similar to Fig. 1 but viewing the device from the rear.

35 Fig. 3 is a perspective view similar to Fig. 2 but illustrating the device with certain parts removed and other parts in a different position.

40 Fig. 4 is a perspective view of a cover which has been removed from the device as illustrated in Fig. 3.

45 Fig. 5 is a horizontal sectional view taken on the line 5—5 of Fig. 1.

Fig. 6 is a fragmentary sectional view on the line 6—6 of Fig. 2.

50 Fig. 7 is a vertical sectional view on the line 7—7 of Fig. 2.

Fig. 8 is a vertical sectional view on the line 8—8 of Fig. 2.

55 Fig. 9 is a fragmentary horizontal sectional view taken on the line 9—9 of Fig. 7.

Fig. 10 is a fragmentary elevational view looking in the direction of the line 10—10 of Fig. 8.

Fig. 11 is a fragmentary sectional view on the line 11—11 of Fig. 10.

Fig. 12 is a fragmentary elevational view looking in the direction of the line 12—12 of Fig. 3.

Fig. 13 is a fragmentary sectional view on the line 13—13 of Fig. 12.

Fig. 14 is a similar view to Fig. 1, but illustrating a further modification of the invention.

Fig. 15 is a perspective view of a portion of the device illustrated in Fig. 14.

Fig. 16 is a vertical sectional view taken on the line 16—16 of Fig. 15.

Fig. 17 is a fragmentary sectional view taken on the line 17—17 of Fig. 16.

Fig. 18 is a fragmentary sectional view taken on the line 18—18 of Fig. 15.

Fig. 19 is a sectional view taken on the line 19—19 of Fig. 18.

Fig. 20 is a sectional view taken on the line 20—20 of Fig. 14.

Fig. 21 is a sectional view taken on the line 21—21 of Fig. 14.

The hand tooling device for using sized gold and other leaf, according to this invention, includes a support member 10 of substantially L-25 shape having a handle element 11 mounted on the top thereof. A stamping die wheel 12 is rotatively mounted on the bottom of the support member 10. A means is provided for heating the stamping wheel 12 and is characterized 30 by a gas supply tube 13 terminating in a burner 14 adapted to direct flame against the side of the stamping die wheel 12.

A substantially horizontal support bar 15 is 35 adjustably mounted on the support member 10. A supply container 16 for a ribbon of gold leaf or similar sized leaf material 17 is mounted upon the support bar 15 and is associated with certain guiding means for guiding a web portion of the ribbon to a position beneath the stamping wheel 40 as hereinafter more fully explained.

The support member 10 is formed with an intermediate shoulder portion 10^a upon which the gas supply tube 13 is adapted to rest. This supply tube is turned several times around the support member to insure the maintenance of this position. The stamping die wheel 12 has a design 18 formed upon its periphery. This design is adapted to cause the transfer of gold leaf or other similar material from the ribbon 50 of sized leaf material 17 upon an object or goods operated on. This design 18 may be ornamental, lettering, or of a different character, as required.

The stamping die wheel 12 is rotatively supported upon the support member 10 in the fol- 55

lowing manner: A tubular bushing 19 is mounted upon one side of the support member 10 and engages into a receiving opening formed in the center of the stamping wheel 12. Another tubular bushing 20 is mounted upon the inner face of the support bar 15 and engages into a concentric circular opening in the other face of the stamping wheel 12. A stud 21 passes through the bushings 19 and 20. Washers 22 and 23 are mounted upon the ends of the stud 21. Wing clamp nuts 24 are threadedly engaged upon the ends of the stud 21 and may be utilized to clamp the parts together. There is a small clearing space 25 between one of the bushings, namely, the bushing 20 and the receiving opening in the stamping wheel 12 which is adapted to prevent the stamping wheel from binding. With this arrangement, even though the nuts 24 are drawn tight, the stamping wheel 12 is free to rotate.

20 The gas supply tube 13 is adapted to be connected at the end 13^a with a gas supply not shown on the drawings. The burner 14 may be used to burn gas supplied through the tube for heating the stamping wheel. The nuts 24 are also utilized to hold the support bar 15 in a predetermined angular position with respect to the support member 10. The supply container 16 is mounted upon the support bar 15 in the following manner: A stud 26 is mounted upon one side 30 of the container 16 and passes through an opening in the support bar 15. A wing clamp nut 27 threadedly engages on the stud 26 and serves to attach the container 16 on the support bar. Within the container 16 there is a central peg member 28 which is fixedly secured coaxial with the container 16 which is circular in transverse cross section.

40 A spool 29 is mounted upon the peg 28. A roll of sized leaf material 17 is mounted on the spool 29. A disc shaped element 30 is engaged within the free side of the container 16 and engages against the side of the ribbon of sized leaf material 17 for holding the roll of ribbon leaf within the container. This disc 30 is provided with 45 several resilient prongs 31 stamped from its face. A cover plate 32 is formed with several hook elements 33 engageable with headed studs 34 mounted upon the container 16 for maintaining its position. The resilient elements 31 rest 50 against the inner face of the cover plate 32 and so resiliently urge the disc 30 against the side of the roll of sized ribbon leaf 17. The cover plate 32 may be removed when required by turning it slightly in a direction to disengage the hook elements 33 from the headed studs 34. One side 55 of the container 16 is formed with a slot 35 through which a web portion of the roll of sized ribbon leaf 17 extends (see particularly Fig. 3). This extending web portion is guided and supported to a position beneath the stamping wheel 12.

60 A channel shaped guide element 36 is attached upon an arm 37 which is pivotally supported on lugs 38 upon the side of the container 16. A clamp screw 39 is associated with the lugs 38 and with the inner end of the arm 37 in a manner so as to frictionally hold the arm in various pivoted positions. The arrangement is such that the clamp screw may be loosened and the arm 37 70 moved to a position as shown in Figs. 1 and 2 to engage the channel guide element 36 across the bottom of the stamping wheel 12. The channel shaped guide element 36 has a portion of its bottom wall cut away, forming an open area 40 immediately at the bottom of the stamping wheel 12

so that the stamping wheel may back up the ribbon of leaf material against an object to be stamped.

A leaf spring 41 is supported at one end upon a link 42 which is adjustably supported on the bar 15. The link 42 is formed with a slot 43. A screw 44 is mounted upon the bar 15 and passes through the slot 43 and is provided with a wing clamp screw 45 which may be tightened to hold the link 42 in adjusted position. The free end 10 of the leaf 41 is adapted to rest against the top face of the web 17 of the sized ribbon leaf to tension the same. The free end of the sized ribbon leaf 17 is guided and supported by a pair of rollers 46 mounted in a block 47 which is pivotally supported by a pintle screw 48 upon one side of the support member 10. The rollers 46 are tensioned toward one another by spring 46'. A spring 50 mounted on the support member 10 acts against the block 47 and urges the wheels 46 20 against the periphery of the wheel 12. Fig. 1 shows the web portion 17 passing upwards around the stamping wheel 12 and between the rollers 46. These rollers 46 preferably should be of wood or other similar soft material. They serve to direct 25 the used portions of the web away from the object being stamped.

The operation of the device is as follows:

As illustrated in Fig. 1, the tooling device is ready to be used. The stamping wheel 12 must 30 be properly heated by the use of the burner 14 or some other heating arrangement. The device as illustrated in Fig. 1 is used by engaging the stamping wheel 12 over an object to be hot stamped. The device preferably should be moved 35 towards the left, as illustrated in Fig. 1. This will cause the stamping wheel 12 to travel over a fresh supply of the web of the sized ribbon 17. The used web will pass upwards between the rollers 46. The design 18 upon the periphery of the 40 stamping wheel will operate to transfer the transferable material from the sized ribbon 17 onto the article being stamped. The proper guiding and tensioning of the sized ribbon 17 is accomplished by the channel guide element 36 and the 45 leaf spring 41.

The roll of ribbon 17 varies in width. The slot 35 is sufficiently wide to permit various widths to pass. The resilient elements 31 will maintain the disc 30 against the side of the roll of ribbon 50 17 irrespective of its width and so properly hold it to discharge its web as required. The support bar 15 may be adjusted to raise or lower the container 16 in order to obtain a proper functioning of the device.

In Figs. 14 to 21, the supply container 16' is 55 illustrated with a hinged cover plate 32'. The channel shaped guide element 36 is attached upon one end of arm 37'. The other end of the arm 37' is pivotally mounted on stud 51 and may be 60 secured at any desired irregular position by a suitable set screw 52, or the like.

A loop member 37^a is provided on the arm 37' to guide the sized ribbon leaf 17 between a slide guide 53 and channel guide element 36. This 65 slide guide is frictionally held in side grooves 54 of the guide member 36.

The sized leaf material 17 and the arm device 37' may be inter-changed for other widths, by swinging hook 55 on pivot 57 on the cover plate 70 32' away from the lock stud 56, so that the cover plate 32' may be lifted on its hinge 32^a.

The disc shaped element 30 is forced against the side of the ribbon of sized leaf material 17, by a conical coil spring 30'. The inner end of this 75

coil spring is welded or is otherwise secured to the cover plate 32' while the outer end freely engages the disc plate 30. In other respects, this form of the invention is similar to the previous form, and 5. the various parts may be recognized by the similar reference numerals.

It is to be understood that any width and color of leaf material may be used with this device and the stamping die wheel may be heated in any 10 desired manner by gas, electricity, etc.

It is to be understood that the main object of the invention is to produce the attachment to the stamping die wheel 12 which enables one to use the hand tooling device to be applied readily to 15 the surfaces of any desired material which is to be stamped or tooled.

While I have illustrated and described the preferred embodiments of my invention, it is to be understood that I do not limit myself to the precise construction herein disclosed, and the right 20 is reserved to all changes and modifications coming within the scope of the invention as defined in the appended claims.

Having thus described my invention, what I 25 claim as new and desire to secure by United States Letters Patent is:

1. A hand tooling device for using sized gold or other sized leaf, comprising a support member having a handle element on the top thereof, 30 a stamping die wheel rotatively mounted on the bottom of said support member, means for heating said stamping wheel, a substantially horizontal support bar adjustably mounted on said support member, a supply container for a ribbon 35 of leaf mounted on said support bar, and guide means for a web portion of said leaf to direct same beneath said stamping wheel, said supply container having a slot in its periphery through which said web portion passes, a spool for supporting a roll of said ribbon being mounted within 40 said container, a disc being supported on said spool and being adapted to engage against the sides of said roll of ribbon, and resilient elements on said disc engaging against a cover on said container.

2. A hand tooling device for using sized gold or other sized leaf, comprising a support member having a handle element on the top thereof, 50 a stamping die wheel rotatively mounted on the bottom of said support member, means for heating said stamping wheel, a substantially horizontal support bar adjustably mounted on said support member, a supply container for a ribbon 55 of leaf mounted on said support bar, and guide means for a web portion of said leaf to direct same beneath said stamping wheel, said supply container having a slot in its periphery through which said web portion passes, a spool for supporting a roll of said ribbon being mounted within 60 said container, a disc being supported on said spool and being adapted to engage against the sides of said roll of ribbon, and resilient elements on said disc engaging against a cover on said container, said cover being provided with 65 hook portions engaging headed studs on said container for the removable support of said cover.

3. A hand tooling device for using sized gold or other sized leaf, comprising a support member 70 having a handle element on the top thereof, a stamping die wheel rotatively mounted on the bottom of said support member, means for heating said stamping wheel, a substantially horizontal support bar adjustably mounted on said support member, a supply container for a ribbon of

leaf mounted on said support bar, and guide means for a web portion of said leaf to direct same beneath said stamping wheel, comprising a channel guide element movably supported on said container and engaging the bottom of said stamping wheel, a resilient leaf adjustably supported on said support bar and bearing against a portion of said web passing through said channel guide element.

4. A hand tooling device for using sized gold or other sized leaf, comprising a support member having a handle element on the top thereof, a stamping die wheel rotatively mounted on the bottom of said support member, means for heating said stamping wheel, a substantially horizontal support bar adjustably mounted on said support member, a supply container for a ribbon of leaf mounted on said support bar, and guide means for a web portion of said leaf to direct same beneath said stamping wheel, comprising a 15 channel guide element movably supported on said container and engaging the bottom of said stamping wheel, a resilient leaf adjustably supported on said support bar and bearing against a portion of said web passing through said channel guide element, and a pair of rollers supported on said support member and guiding the free end of said web portion.

5. A hand tooling device for using sized gold or other sized leaf, comprising a support member having a handle element on the top thereof, a stamping die wheel rotatively mounted on the bottom of said support member, means for heating said stamping wheel, a substantially horizontal support bar adjustably mounted on said support member, a supply container for a ribbon of leaf mounted on said support bar, and guide means for a web portion of said leaf to direct same beneath said stamping wheel, a spool for supporting a roll of said ribbon being mounted 30 within said container, a disc being supported on said spool and being adapted to engage against the sides of said roll of ribbon, a pivotally mounted cover for closing said container and a resilient element on said disc engaging against said cover 35 for urging said disc against said roll, and being secured thereto, said cover being supported on a hinge.

6. A hand tooling device for using sized gold or other sized leaf, comprising a support member 50 having a handle element on the top thereof, a stamping die wheel rotatively mounted on the bottom of said support member, means for heating said stamping wheel, a substantially horizontal support bar adjustably mounted on said support member, a supply container for a ribbon of leaf mounted on said support bar, and guide means for a web portion of said leaf to direct same beneath said stamping wheel, a spool for supporting a roll of said ribbon being mounted 55 within said container, a disc being supported on said spool and being adapted to engage against the sides of said roll of ribbon, a pivotally mounted cover for closing said container, a resilient element on said disc engaging against said cover 60 for urging said disc against said roll, and being secured thereto, a stud projecting from said container through an opening in the said cover, and a hook rotatively supported on the cover, adapted to engage the said stud for keeping the cover 65 closed on the container.

7. A hand tooling device for using sized gold or other sized leaf, comprising a support member having a handle element on the top thereof, a stamping die wheel rotatively mounted on the 70

- bottom of said support member, means for heating said stamping wheel a substantially horizontal support bar adjustably mounted on said support member, a supply container for a ribbon or leaf mounted on said support bar, and guide means for a web portion of said leaf to direct same beneath said stamping wheel, a spool for supporting a roll of said ribbon being mounted within said container, a disc being supported on said spool and being adapted to engage against the sides of said roll of ribbon, a pivotally mounted cover for closing said container and a resilient element on said disc engaging said cover for urging said disc against said roll, and being secured thereto, said cover being supported on a hinge, said guide means comprising a channel guide element movably supported on said container and engaging the bottom of said stamping wheel, a side plate adjustably supported on said support bar and bearing against a portion of said web passing through said channel guide element, for adjustably guiding said web.
8. A hand tooling device for using sized gold or other sized leaf, comprising a support member having a handle element on the top thereof, a stamping die wheel rotatively mounted on the bottom of said support member, means for heat-
- 5
